DOOR LOCK

Walter R. Schlage, Burlingame, Calif., assignor
to Schlage Lock Company, San Francisco,
Calif., a corporation of California

Application July 2, 1940, Serial No. 343,570

23 Claims. (Cl. 70—146)

This invention relates to door locks of the type disclosed in my former Patent No. 2,018,093, entitled "Door lock," issued October 22, 1935, and especially to improvements and additions to the structure there disclosed.

The patent above referred to, briefly stated, embodies a door lock which is provided with an inner and an outer knob, a key-actuated mechanism in the outer knob whereby the door may be opened under certain conditions from the exterior, and a manually actuated member in the inner knob for dogging the outer knob against operation and for simultaneously displaying an indicator and obstructing the key passage, so as to prevent opening of the door from the outside except by the use of an emergency key.

The manually actuated member comprises a push button mounted in the inner knob. A bar is attached thereto, and this bar actuates the indicator, the key-obstructing means, and finally the dogging member whereby the outer knob is dogged against rotation. When the button is depressed, no one can enter from the exterior except a person possessing an emergency key; hence if it is desired to permit entrance by an ordinary key, the indicator and key-obstructing means must be released without releasing the dogging member. Such release is provided, as it is accomplished by depression of a latch bolt.

The present invention relates to the dogging mechanism, the indicator and the key-obstructing or shut-out mechanism of a lock of this character, and the object is to simplify and improve the construction and operation thereof; to provide two push buttons, one which actuates the dogging mechanism whereby the outer knob is dogged against operation, and a second button the indicator and the key shutout; to provide two push buttons which are independently operable; and further, to provide means whereby one button, or both of them, may be released in unison by mere rotation of the inner knob, and one of them by depression of the latch bolt.

The invention is shown by way of illustration in the accompanying drawings, in which

Fig. 1 is a horizontal central longitudinal section of the lock showing it mounted in a door, said view showing the two push buttons extended;

Fig. 2 is a similar section showing one of the push buttons depressed and the second push button partially depressed;

Fig. 3 is a similar section showing both push buttons fully depressed;

Fig. 4 is a central longitudinal section taken at right angles to Fig. 1;

Fig. 5 is a cross section taken on line V—V of Fig. 4;

Fig. 6 is a perspective view of the main push button bar;

Fig. 7 is a perspective view of the secondary push button bar;

Fig. 8 is a perspective view of a spring-retaining cage used in connection with the main push button;

Fig. 9 is a perspective view, partially broken away, of the main push button;

Fig. 10 is a perspective view of a pin retaining collar used in connection with both push buttons;

Fig. 11 is a perspective view of the secondary push button.

Fig. 12 is a perspective view of the main push button bar dogging member;

Fig. 13 is a perspective view of the inner door knob spindle;

Fig. 14 is a perspective view of the dogging member whereby the outer knob spindle is dogged against rotation;

Fig. 15 is a perspective view of a spring seat used in connection with the dogging member shown in Fig. 14;

Fig. 16 is a perspective view of the retractor;

Fig. 17 is a perspective view of the housing of a pin tumbler cylinder lock;

Fig. 18 is a perspective view of the indicator and the key shutout plate;

Fig. 19 is a perspective view of a guide disc used in connection with the key shutout plate;

Fig. 20 is a perspective view of a driver blade used in connection with the pin tumbler cylinder lock;

Fig. 21 is a perspective view of a retaining collar used in connection with the rotatable core of the pin tumbler cylinder lock;

Fig. 22 is a perspective view of the outer door knob spindle; and

Fig. 23 is a perspective view of the key-actuated spindle.

Referring to the drawings in detail, and particularly Figs. 1 and 5, A indicates in general a lock housing in which is mounted a retractor B, and C indicates a housing which carries a latch bolt D, a retractor bar 2, to which the latch bolt is secured, and a spring 3 which surrounds the retractor bar and normally maintains the latch bolt in projected position.

The lock housing indicated at A will herein-after be referred to as the latch bolt actuating

unit, and the housing C as the latch bolt unit. The housing A, as previously stated, encloses and supports the retractor B, the housing is provided with two hub portions *a*—*a* and these form a support for the pair of spindles E and F. Each spindle is provided with a knob, one knob being indicated at 4 and the other at 5. The knob 4 will hereinafter be referred to as the outer knob and the knob 5 as the inner knob. The knobs are suitably secured to their respective spindles, and when either knob is rotated the cooperating spindle will be rotated. The inner knob spindle is shown in perspective in Fig. 13, and the outer knob spindle is shown in perspective in Fig. 22.

It will be noted by referring to Figs. 13 and 22 that the inner end of each spindle is provided with a rollback member, one such member being indicated at 6 and the other at 6a. These rollback members engage the retractor B when the spindles are rotated, and impart an endwise movement to the retractor within the housing, and during such movement also impart endwise movement to the latch bolt D to cause retraction thereof. The retractor B is best shown in Figs. 5 and 16. It consists of spaced side plates 7, on the outer surfaces of which are formed shoulders 8 and 8a. The side plates are connected at their inner ends by a central crossbar 9, and the outer ends terminate in crossbars 10 which straddle and engage lugs 10a formed on the inner end of the retractor bar 2. The rollback members formed on the inner ends of the respective spindles will engage the respective shoulders 8 and 8a on opposite sides of the retractor when the spindles are rotated, and it is through this engagement that endwise movement is imparted to the retractor and to the retractor bar 2, so as to retract the latch bolt D, projection of the latch bolt D being insured by spring 3 which is compressed during the retracting movement.

The outer knob spindle F carries an interior spindle, shown in Figs. 1 to 4 and 23, which is indicated by the numeral 11. This spindle will hereinafter be referred to as the key spindle, as it is rotated by means of a key-actuated mechanism only. This spindle is also provided with a rollback member such as shown at 6b, and when the spindle 11 is rotated by the key-actuated mechanism the rollback member 6b engages the shoulders 8a on the retractor and thus imparts endwise movement thereto and to the retractor bar and the latch bolt D. Hence it is possible to retract the latch bolt either by the key-actuated spindle 11 or by either of the knob-actuated spindles E and F.

The door lock illustrated in the present instance is provided with a key-actuated pin tumbler type of lock generally indicated at G (see Fig. 17). This lock is mounted in the outer end of the spindle F and is disposed within the knob 4 carried thereby. The inner spindle E has two push buttons mounted therein which are generally indicated at 14 and 15. These normally assume a projected position with relation to the end of the inner spindle and the knob carried thereby, but they may be depressed for purposes hereinafter to be described.

The key-actuated pin tumbler mechanism is of standard construction and requires no particular explanation. It should suffice to say that it is provided with a rotatable core or cylinder plug 16 in which is formed a key passage for the reception of a key such as shown at 17 (see Fig. 4). When this key is inserted, the plug 16 may be

rotated, and during such rotation, movement is transmitted to rotate the key spindle 11, so as to cause retraction of the latch bolt D and opening of the door by means of a key.

5 The connection between the plug member 16 and the key spindle is best shown in Figs. 4 and 17 to 23 inclusive. The inner end of the plug member projects through the inner end of the housing of the cylinder lock G (see Fig. 17), and 10 is provided with a cross-slot 18. In this slot is mounted a crossbar 19 (see Fig. 18), which carries two pins indicated at 20 and 21. Holes are drilled through the plug member 16 (see Fig. 1) for the reception of these pins. A spring 20a 15 cooperates with the pin 20 to normally maintain the crossbar 19 in engagement with the inner end of a driver blade 22, as will hereinafter be described. The crossbar 19 functions as a key-obstructing or shutout member, as will later be 20 more fully understood, while the pin 21 functions as an indicator.

The projecting inner end of the plug, which is slotted as at 18, is threaded on the exterior and carries a coupling collar 23 (see Figs. 4 and 21), 25 this coupling collar when applied being secured in any suitable manner. Between the coupling collar and the end of the plug is disposed a washer 24. This has a cross-slot formed therein, as indicated at 25, and this slot functions as a 30 guide and support for the driver blade 22 which projects therethrough. The coupling member accordingly forms a coupling or connection between the rotatable core and the driving blade 22, and as this projects into a disc 26 secured 35 in the outer end of the key spindle (see Fig. 23), and the disc is provided with a slot 27, a coupling is formed not only between the core of the key-actuated pin tumbler housing and the driver blade, but also a coupling is made with the key spindle. Hence when a key is inserted and the core rotated, rotational movement is transmitted to the driver blade and by the driver blade to disc 26 and the key spindle, permitting retraction 40 of the latch bolt, or in other words opening of the door from the exterior by means of a key.

The inner spindle and knob, as previously stated, carry the two push buttons indicated at 14 and 15. Their construction and operation will now be described. First of all, it might be stated that the button 14 will hereinafter be referred to as the main button and the button 15 as the secondary button. The main button is best shown in Fig. 9. It is pressed on or otherwise secured to a cage member shown in Fig. 8; the portion onto which it is pressed is indicated at 55 27. This member has a disc-like base 28 with a central opening 29 formed therein, and it has two extending legs 30 and an inner disc 31 in which is formed a central opening 32. Also it is provided with a radially extending lug 33. This member forms a cage and a support for the main button 14. It is slidably mounted in the outer end of the spindle E, but it is held against rotation by the lug 33 which extends into a slot 60 formed in the spindle (see Fig. 1). A spring 34 normally maintains the cage in a position where both buttons are projected, the spring being interposed between a stationary cross-plate 35, secured in the spindle, and the inner end 31 of the cage. The main button 14 (see Fig. 9) has an annular inwardly-extending flange 36 formed in its outer end. This flange forms a sleeve in 65 which the secondary button 15 is supported and in which it is guided, a flange 15a on said button limiting outward movement. The two buttons

serve the function of imparting longitudinal movement to a pair of bars such as shown in Figs. 6 and 7. The bar shown in Fig. 6 is the main button bar and is indicated by the numeral 37, and the bar shown in Fig. 7 is the secondary button bar. The last named bar will be referred to by the numeral 38. The bar 37 is provided with a pair of laterally extending shoulders 39, and the bar 38 with a pair of laterally extending shoulders 39a. The bars extend through the inner spindle and the retractor, and partially into the outer spindle. The shoulders 39 and 39a engage the inner disc-shaped end 31 of the main button supporting cage, and that limits their outward movement. The ends of the bars, which extend beyond the shoulders 39 and 39a, both extend into the interior of the button 15. The extension on one bar, that is, the main bar 37, is slightly less than the extension on the bar 38; hence when both buttons are extended the secondary button will engage only the end of the bar 38. The bar 37 serves the function of actuating a dogging member 40 (see Fig. 14) which is provided with a radially extending dogging leg 41. This dog serves the purpose of dogging the outer spindle and knob against rotation. The bar 38, on the other hand, functions to actuate the key shutout and indicator.

The function of bar 37 will first be described. When the button 14 is pushed inwardly by finger pressure, button 15 will follow with it, as the annular flange 36 on the main button engages the collar 15a on the button 15. Hence by pushing inwardly on the main button both buttons will be depressed. As they move inwardly the cage to which the main button is secured will also move inwardly; hence the inward movement will be limited by the lug 33 traveling in the slot in the knob spindle. During this movement the end 31 of the cage will engage the shoulders 39 and 39a of the respective bars 37 and 38, and both bars will accordingly be moved longitudinally in the direction of arrow a (see Fig. 1).

Both bars are provided with aligning shoulders 42. These are engaged by a dog 43, and when engaged by said dog both buttons will be secured in the depressed position. During the inward movement of the two bars into engagement with the dog 43 the inner end of the bar 37, which has a shoulder 37a formed thereon, engages the dogging member 40 and pushes it into the inner end of the outer knob spindle. A slot is formed in this spindle, as shown at 44. The dog 41 enters the slot and it also enters a slot formed in the housing A, thereby dogging the outer spindle against rotation. The door may, however, be opened from the outside by means of the key shown at 17, as insertion of the key will permit rotation of the core within the pin tumbler cylinder lock, and this will, through the mechanism previously described, rotate the key spindle 11, which in turn will actuate the retractor and thereby retract the latch bolt and permit opening of the door.

Such opening by means of a key can, however, be prevented by depressing the second button 15. That is, both buttons, as previously described, are moved inwardly until the shoulders 42 of the respective bars 37 and 38 are engaged by the dog 43. The button 15 may then be depressed a second time, or moved a greater distance inwardly, such movement being permitted by slotting the bar at the point indicated at 45 (see Figs. 1 and 7). When the bar 38 is moved by means of the inner button its inner end, or that indicated at

38a, will engage a button 47. This button will in turn engage the inner end of the driver blade 22, and the driver blade will in turn engage the crossbar 19 and thereby force the same, together with the pins 20 and 21, in an outward direction, the position of these parts when so actuated being shown in Fig. 3. That is, Fig. 1 shows both buttons in the full extended position; Fig. 2 shows the two buttons depressed, and that means that 10 the outer spindle and knob have been dogged against operation; while Fig. 3 shows the button 15 further depressed, which means that the indicating pin 21 projects beyond the outer end of the pin tumbler cylinder lock, and it also means that the cross-plate 19 has been moved inwardly to a position where it does not permit complete insertion of a key. It is for this reason that it is referred to as a key shutout member. In this position the outer knob and spindle are dogged against operation, the indicator is displayed, and no key can be inserted except an emergency key; that is, the usual key will be a normal key such as shown in Fig. 4, which may be inserted to 15 operate the pin tumbler lock when it may be fully inserted, but when the crossbar assumes the position shown in Fig. 3 the key can not be fully inserted and thus can not actuate or release the pin tumblers to permit rotation of the core. An emergency key may, however, be provided 20 which will release the pin tumblers and which may be inserted when the crossbar assumes the position shown in Fig. 3. This emergency key of course will only be in the possession of a certain individual, and is provided for emergency 25 use only. The normal key, however, is shut out at such times and can not be employed.

Before describing the manner in which the buttons, together with the bars actuated thereby, are released and returned to normal position to 30 permit normal operation of the lock, it is desired to describe the construction of the dog 43. This dog is best shown in Fig. 12. It consists of a substantially circular disc 43a, to one edge of which the dog 43 is attached. The disc has a central opening formed therein to permit the bars 37 and 38 to extend therethrough, and it has a radially projecting lug 43b which projects into a guide slot in the spindle, so as to permit the dog to be rotated with the spindle when the 35 spindle is rotated. The dog 43 is disposed at an angle with relation to the disc 43a, and the disc rests on or engages the stationary cross-plate 35 secured in the spindle (see Figs. 1, 2 and 3). The disc is engaged by a spring 43c which exerts a continuous pressure thereon. When all parts are 40 in normal position, the dog 43 rides on the edges of the respective bars 37 and 38, as shown in Fig. 1, but when the bars are moved inwardly by means of the buttons the shoulders will be moved to position beyond the inner end of the dog 43, and this will then swing inwardly and engage behind the shoulders, thus preventing return of the 45 bars.

To release the dog, so as to permit return of the buttons and bars to normal position, it is necessary to rotate the inner spindle E by means of the knob. During such rotation of the inner spindle, disc 43a to which the dog is secured will also be rotated, as the lug 43b extends into a slot 50 in the spindle. During such rotation the dog will swing towards the flat side of the bars, and thus swing out of engagement with the shoulders, and when this happens, both bars are released and are returned to normal position by 55 their respective springs. That is, the button 47

is actuated by a spring 41a. Hence when the bar 38 is released the spring 41a will push the button 47 against the dogging member 40, and it will also exert pressure on the end of the bar 38, thereby restoring it to normal position.

This spring also functions to move the dog 40 to released position, and as the dog 40 engages the shoulder 37a of the bar 37, this will also return to normal position. The main button will return to normal position due to the pressure of the spring 34, and the button 15 will return to normal position due to the pressure exerted by a spring 41a. A collar 15d, by the way, is shown in Figs. 1 and 10; it merely serves as a closure or cap to cover a pin 15c which extends through the slot 45 of the bar 38 and a hole 45a formed in the bar 37, the collar being held in position by a spring 15b. This pin and cap or collar are employed for assembling purposes, that is, to retain the two bars in the cage of the main button during assembly of the lock parts; and the pin also serves the function of limiting inward movement of the button 15 with relation to the button 14, the length of the slot 45 being the limiting factor.

When the dog 43 engages the shoulders 42 of the respective bars, it secures both bars and buttons against outward movement. It should be remembered, however, that the button 15 and the bar connected therewith can assume a second position, or that shown in Fig. 3. That means that the bar 38 will move away from the dog 43 as it is moved an added distance inwardly, the added distance being the movement of the button 15 when assuming the position shown in Fig. 3. Hence, means must be provided for dogging or latching the bar 38 when it assumes its innermost position. This is accomplished by providing a latch, having two inwardly-extending arms 50. This latch is carried by the retractor B, and it is held against the edges of the bars at all times by a spring 51. On the side of the bars adjacent the latch arms 50 are formed notches, there being two notches 52 in the bar 37 and two notches 53 in the bar 38. These notches are out of alignment at all times except when the bar 38 assumes its innermost position. In that position the notches 53 align not only with the notches 52 but also with the latch arms 50, and the latch will accordingly move inwardly into said notches and dog or latch both bars against release. Hence the dog 43 serves the purpose of securing both bars in their first depressed position, and the latch 50 serves the function of securing both bars when the bar 38 assumes its innermost position. Both bars are, however, simultaneously released when the inner knob and spindle are rotated, as such rotation will cause the rollback member 6 on the inner spindle to engage one of the side shoulders 8 and 8a of the retractor. When this happens the retractor is moved inwardly, and when it moves inwardly latch 50 moves with it, and out of engagement with the notches 52 and 53, thus simultaneously releasing both bars, and when these bars are released the outer spindle will be undogged, the indicator will be retracted and so will the key shutout member.

Plainly speaking, by providing two buttons, one button may be employed for the purpose of dogging the outer spindle against rotation, and the second button may be employed for the purpose of actuating the indicator and the key shutout mechanism. The operation of depressing the two buttons performs only one function; that is, it accomplishes dogging of the outer spindle.

Both buttons may be released from this position by rotating the inner spindle by means of the knob. On the other hand, if both buttons are depressed to the first position, and then the second button is further depressed, the outer knob will be dogged, the indicator will be displayed, and the key shutout will assume obstructing position. In that position both buttons and their bars are retained by the latch 50, and both buttons and bars are releasable by rotation of the inner knob and spindle. Hence it is possible to release the main button when this functions only to dog the outer spindle, and it is also possible to release both buttons when both have been depressed to their dogging positions.

The main button and bar, as previously stated, serve the function of dogging the outer spindle and knob against rotation, and when they are moved or depressed to dogging position they are held in that position by means of the dog 43; and as this can only be released by rotation of the inner knob and spindle, it becomes possible for a person leaving a room to lock the door, as he or she in leaving the room will only have to depress the main button and then close the door upon going out. During the closing of the door the latch bolt will engage the striker plate and will be forced inwardly. Such inward movement is in no way obstructive; that is, the bar 2 having the lugs 10a formed on its inner end (see Fig. 5) can move freely inwardly without imparting movement to the retractor, but the lugs 10a will engage the arms of the latch 50 and thereby force this inwardly. This member, as previously stated, is movable independently of the retractor.

This is important, as will appear. If children are in a room, it is possible that they might open the door and depress the main button and thereafter the secondary button, and then slam it as they leave the room. If some means were not provided for releasing the secondary button from dogging position under such conditions, the door would be permanently locked and could not be opened except by means of an emergency key. This is prevented in the present instance as follows:

If the secondary button is pushed inwardly after the main button has been depressed, the bar connected therewith will extend the indicator, and at the same time obstruct the key passage, thus making it impossible for anyone to enter except the person in possession of the emergency key. When the secondary button and bar are thus depressed, they are secured in that position by the latch 50. During slamming or closing of the door, the latch bolt will, as previously stated, be depressed. The bar 2, connected therewith and having the lugs 10a on its inner end, will also be depressed, or in other words, move inwardly, and when it does so, the lugs 10a engage the arms of the latch 50, thereby pushing it inwardly. In so doing the secondary latch bar and button are released and they will immediately return to inoperative position and the key obstructing means and the indicator will at the same time return to normal position. Thus, while the door will still remain locked while it is closed, it can be opened by an ordinary key. Hence any danger of locking out a person who is in possession of an ordinary key is avoided, as the only time the door can be locked against an ordinary key is when the person locking the door remains in the room and purposely or with intent depresses the secondary button. On the

other hand, a person may lock the door by merely depressing the main button and then going out and closing the door; when a door is so locked, it can be opened by an ordinary key.

While certain features of my invention have been more or less specifically described and illustrated, I nevertheless wish it understood that changes may be resorted to within the scope of the appended claims.

Having thus described my invention, what I claim and desire to secure by Letters Patent is:

1. In a door lock a latch bolt, an inner and an outer actuator for the latch bolt, a key-actuated mechanism operable from the outer side to retract the latch bolt, means on the inner side for rendering the outer actuator inoperative, and other and independently operated means on the inner side for rendering the key mechanism inoperative except by an emergency key.

2. In a door lock a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, and means on the inner side for releasing the outer actuator and the mechanism which renders the key mechanism inoperative.

3. In a door lock a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, and means on the inner side for releasing, independently or in unison, the outer actuator and the mechanism which renders the key mechanism inoperative.

4. In a door lock a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, an inner door knob, and means actuated by rotation of said knob for releasing the outer actuator and the mechanism which renders the key mechanism inoperative.

5. In a door lock a latch bolt, an inner and an outer knob, means actuated by either knob for retracting the latch bolt, a key-actuated mechanism in the outer knob for retracting the latch bolt, means on the inner side of the lock for rendering the outer knob inoperative to retract the latch bolt, and other means on the inner side of the lock for rendering the key mechanism inoperative.

6. In a door lock a latch bolt, an inner and an outer knob, means actuated by either knob for retracting the latch bolt, a key-actuated mechanism in the outer knob for retracting the latch bolt, means on the inner side of the lock for rendering the outer knob inoperative to retract the latch bolt, other means on the inner side of the lock for rendering the key mechanism inoperative, and means actuated by rotation of the inner knob for releasing the outer knob and the mechanism which renders the key mechanism inoperative.

7. In a door lock a latch bolt, an inner and an

outer knob, means actuated by either knob for retracting the latch bolt, a key-actuated mechanism in the outer knob for retracting the latch bolt, a depressible button in the inner knob for dogging the outer knob against operation, and a second depressible button in the inner knob for rendering the key mechanism inoperative.

8. In a door lock a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, and means actuated by rotation of the inner knob for releasing both buttons to permit undogging of the outer knob and for rendering the key mechanism operative.

9. In a door lock a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, said buttons being depressible in unison and when so depressed dogging the outer knob against operation, said second button adapted to be further depressed and when so depressed rendering the key mechanism inoperative, and means actuated by rotation of the inner knob for releasing both buttons to permit undogging of the outer knob and for rendering the key mechanism operative.

10. In a door lock a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, said buttons being depressible in unison and when so depressed dogging the outer knob against operation, said second button adapted to be further depressed and when so depressed rendering the key mechanism inoperative, a pair of independently operable dogging members for securing the buttons in their respective depressed positions, means actuated by rotation of the inner knob for releasing both dogs, and means for returning both buttons to normal position when released.

11. In a door lock a latch bolt, an inner and an outer spindle, a retractor actuated by either spindle to retract the latch bolt, a key-actuated mechanism in the outer spindle for retracting the retractor and latch bolt, a depressible button mounted in the inner spindle, a dogging member actuated by said button to dog the outer spindle against operation, a second button in the inner spindle, means actuated by said button for rendering the key mechanism inoperative, means actuated by rotation of the inner spindle for releasing both buttons, and other means for returning the buttons to normal extended position.

12. In a door lock a latch bolt, an inner and an outer spindle, a retractor actuated by either spindle to retract the latch bolt, a key-actuated mechanism in the outer spindle for retracting the retractor and latch bolt, a depressible button mounted in the inner spindle, a bar connected with said button and extending through the inner spindle and the retractor, a dogging member actuated by said bar to dog the outer spindle

against rotation, a secondary depressible button mounted within the first named button, a second bar connected with the secondary button and extending through the inner spindle and the retractor, means actuated by said secondary bar for rendering the key mechanism inoperative, said buttons adapted to be depressed in unison and when so depressed imparting movement to both bars and the first named bar causing dogging of the outer spindle, a dogging member engaging both bars and retaining them when moved by depression of both buttons, said last named bar releasing both bars when the inner spindle is rotated, and spring means for returning both bars and the connected buttons to normal position.

13. In a door lock a latch bolt, an inner and an outer spindle, a retractor actuated by either spindle to retract the latch bolt, a key-actuated mechanism in the outer spindle for retracting the retractor and latch bolt, a depressible button mounted in the inner spindle, a bar connected with said button and extending through the inner spindle and the retractor, a dogging member actuated by said bar to dog the outer spindle against rotation, a secondary depressible button mounted within the first named button, a second bar connected with the secondary button and extending through the inner spindle and the retractor, means actuated by said secondary bar for rendering the key mechanism inoperative, said buttons adapted to be depressed in unison to impart inward movement to both bars within the inner spindle, a dogging member for retaining the bars when moved, said second button adapted to be further depressed after the first depression of both buttons, so as to impart further movement to the second bar, means for retaining the second bar and button after the second depression, manually actuated means for releasing both buttons and bars, and means for returning them to normal position.

14. In a door lock a latch bolt, an inner and an outer spindle, a retractor actuated by either spindle to retract the latch bolt, a key-actuated mechanism in the outer spindle for retracting the retractor and latch bolt, a depressible button mounted in the inner spindle, a bar connected with said button and extending through the inner spindle and the retractor, a dogging member actuated by said bar to dog the outer spindle against rotation, a secondary depressible button mounted within the first named button, a second bar connected with the secondary button and extending through the inner spindle and the retractor, means actuated by said secondary bar for rendering the key mechanism inoperative, said buttons adapted to be depressed in unison to impart inward movement to both bars within the inner spindle, a dogging member for retaining the bars when moved, said second button adapted to be further depressed after the first depression of both buttons, so as to impart further movement to the second bar, means for retaining the second bar and button after the second depression, said depression of the buttons in unison causing dogging of the outer spindle only and said further depression of the secondary button rendering the key mechanism inoperative, means for releasing both buttons and bars, and means for returning them to normal position.

15. In a door lock a latch bolt, an inner and an outer knob, means actuated by either knob for retracting the latch bolt, a key-actuated

mechanism in the outer knob for retracting the latch bolt, means on the inner side of the lock for rendering the outer knob inoperative to retract the latch bolt, other means on the inner side of the lock for rendering the key mechanism inoperative, and means actuated by depression of the latch bolt for releasing the means which render the key mechanism inoperative.

16. In a door lock a latch bolt, an inner and an outer knob, means actuated by either knob for retracting the latch bolt, a key-actuated mechanism in the outer knob for retracting the latch bolt, means on the inner side of the lock for rendering the outer knob inoperative to retract the latch bolt, other means on the inner side of the lock for rendering the key mechanism inoperative, means actuated by depression of the latch bolt for releasing the means which render the key mechanism inoperative, and means actuated by rotation of the inner knob for releasing the outer knob.

17. In a door lock a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, and means actuated by depression of the latch bolt for releasing the second depressible button only.

18. In a door lock a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, means actuated by depression of the latch bolt for releasing the second depressible button only, and means actuated by rotation of the inner knob for releasing the outer knob.

19. In a door lock, a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, and means actuated by depression of the latch bolt for releasing said means to render the key mechanism operative.

20. In a door lock, a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, and means actuated by rotation of the inner actuator for releasing the outer actuator and for simultaneously rendering the key mechanism operative.

21. In a door lock, a latch bolt, an inner and an outer actuator for the latch bolt, a key-actuated mechanism operable from the outer side to retract the latch bolt, means on the inner side for rendering the outer actuator inoperative, other and independently operated means on the inner side for rendering the key mechanism inoperative except by an emergency key, and means

actuated by depression of the latch bolt for rendering the key mechanism operative but leaving the outer actuator inoperative.

22. In a door lock, a latch bolt, an inner and an outer knob, means actuated by either knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, and means actuated by depression of the latch bolt for releasing only the button which actuates the key mechanism.

23. In a door lock, a latch bolt, an inner and an outer knob, means actuated by either

5 knob for retracting the latch bolt, a key-actuated mechanism in the outer knob for retracting the latch bolt, a depressible button in the inner knob for dogging the outer knob against operation, a second depressible button in the inner knob for rendering the key mechanism inoperative, said buttons being depressible in unison and when so depressed dogging the outer knob against operation, said second button adapted to 10 be further depressed and when so depressed rendering the key mechanism inoperative, and means actuated by depression of the latch bolt for releasing the key actuating button only to render the key mechanism operative.
